MAGNETIC CHANGE-OVER VALVE

William Robert Eddy, Bartlesville, Okla., assignor
to Phillips Petroleum Company, a corporation
of Delaware

Application December 18, 1950, Serial No. 201,324

7 Claims. (CL. 62—1)

1

This invention relates to a dispensing system for high pressure fluids and includes a device for automatically changing withdrawal connections from one source of fluid to another. In one aspect, it relates to a fully automatic changeover device for the transfer of withdrawal connections from one source of high pressure gas to another upon decrease in pressure of the first source. In another aspect, it relates to a fully automatic changeover and cylinder indicating assembly for the transfer of withdrawal connections from one source of a high pressure gas to another upon decrease in pressure from the first source with the indication of which source of gas is depleted.

In dispensing fluids under pressure from containers as, for example, liquefied petroleum gas, a device for automatically changing withdrawal connections from one container to another is desirable to insure an uninterrupted flow of the fluid. Various semi-automatic and fully automatic changeover devices have been proposed heretofore. The purpose of my invention is to provide a dispensing system including a fully automatic changeover device which possesses several desirable characteristics which will be realized upon reading the following specification.

An object of my invention is to provide an improved changeover device which is fully automatic and of simplified design and construction while being efficient and positive in its operation. A further object of my invention is to provide an automatic changeover device which is composed of a minimum number of parts and depends for its operation on decrease in pressure from one of the sources of supply. Another object of my invention is to provide a changeover device for liquefied petroleum gas dispensing systems which will give visual indication as to which of the two sources of gas is being used. Still another object of my invention is to provide a fully automatic changeover device for liquefied petroleum gas dispensing systems which will give visual indication as to which of two sources of gas is being used and for use in conjunction with the device to indicate visually when one tank is empty and, further, to indicate visually which tank is empty. Many other objects and advantages of my changeover device will be realized upon reading the following disclosure which, taken with the attached drawing, forms a part of this specification.

In the drawing, Figure 1 is an elevational view, partly in section, of my indicating and changeover device. Figure 2 is an end view of the appa-

ratus of Figure 1. Figure 3 is a sectional view of the apparatus taken on the line 3—3 of Figure 1. Figure 4 shows, in part, an LPG dispensing system with my automatic changeover and indicating device.

Referring now to the drawing, and specifically to Figures 1, 2, and 3, the apparatus includes a main body member 11. This body member has a conduit of varying diameter passing from one end to the other and also contains a side conduit communicating from the exterior to about a midpoint of the main conduit. Various sections of the main conduit to the body member 11 have different diameters. For example, beginning at the left of Figure 3, the first portion of the conduit is of relatively large diameter and is threaded to accommodate the threaded end of the nozzle fitting 15. At the end of this threaded section is a plain, smooth section of conduit which is adapted to accommodate a ring washer 17. The next section of the conduit is of slightly smaller diameter than those heretofore mentioned but is in axial alignment therewith. The change in diameter from the larger diameter section which accommodates the resilient washer and that which accommodates member 22 serves as a shoulder against which the resilient washer 17 is placed. From the section of conduit which contains the element 22 is a conduit section 27a of relatively small diameter extending farther to the right and downward somewhat. In the right-hand half of the body 11 is a conduit 27b which is just exactly like conduit 27a in the left-hand half of the body member 11. The two small diameter conduit sections 27a and 27b meet at the center of the body member 11 and communicate with the passage 38 or outlet conduit. When in use, the nozzle fittings 15 and 16 lead the gas from storage cylinder conduits to the changeover and the gas leaves the body member 11 through the side outlet passage 38 from which it is conducted through pressure reducing apparatus, etc., to the appliances.

The discharge ends of the nozzle fittings 15 and 16 are made in the form of valve seats so that the resilient sealing members 25 and 26, when pressed against the valve seats, will form effective seals. Elements 22 and 23 are magnets to which the resilient sealing members 25 and 26, respectively, are attached. These magnets are intended to force the resilient members 25 and 26 against the respective valve seats of the nozzle fittings 15 and 16 to seal off the flow of gas from a cylinder or to open the nozzle fittings to the flow of gas.

To the underside of a rotor member 13 are attached two magnets 24a and 24b in the manner illustrated. As illustrative of the arrangement of these magnets, for example, the inner end of the magnet 22 may be the north pole, accordingly the outer or adjacent end of the magnet 24a is a north pole. In other words, the magnets 22 and 24a are arranged with like polarities adjacent. The two magnets 23 and 24b are disposed relative to each other in the opposite manner. In other words, when handle 14 is rotated 180° the adjacent poles of magnets 22 and 24b are of unlike polarity so that they will attract each other and at the same time the adjacent poles of magnets 23 and 24a will repel each other. If it is desired, the magnets 24a and 24b may be separate magnets as just described; or, if desired, they may be one large magnet with an opening in the center for installation around a spindle 12. These magnets 24a and 24b, whether one magnet or two magnets, are attached to the bottom of the rotor 13, and this entire assembly is fitted around the spindle 12, as shown. A pair of lock nuts 36 or other means may be used for holding this rotor assembly in place. An indent assembly 39, as shown, is provided for making certain that the handle 14 and the rotor 13 will remain in a desired position.

The threaded outlet 37 which contains passage 38 is a straight member as shown and is preferably attached to an outlet pipe 57 by means of an L 37a so that the handle 14 of the rotor 13 will be moved in a vertical plane when the apparatus is in operation. This arrangement is desired so when the apparatus is installed in an outdoor location that rain or freezing will not interfere with the ease of rotation of the rotor member 13.

To the left of the resilient member or washer 17 in the nozzle member 15 is provided an opening 20 (Figure 1). This opening 20 is intended to provide fluid communication from the tube leading to the nozzle member 15 to a circular section bounded by the nozzle member 15, the resilient washer 17, and the body member 11.

In Figure 1 are shown webs 43 and 44. Web 43 contains a conduit 18 which leads from the circular space, mentioned above, and bounded by the nozzle member 15, the resilient washer 17 and the body member 11, to a point within the space of the indicator housing member 31. This indicator housing member is composed of two parts, the left-hand part identified by reference numeral 41 is cast as an integral part of the main body member 11. A removable part of this indicator housing is identified by reference numeral 42. Assembled between these two auxiliary housing members 41 and 42 is a diaphragm 29. To either side of this diaphragm member 29 are attached some red indicators or flags 33 and 33a. To the auxiliary housing member 41 is fixed a transparent window 45 through which the red flag or indicator 33 may be seen. The transparent window 46 is provided in the removable section 42 of the auxiliary housing member 31 so that the indicator 33a may be seen. The lengths of the indicators 33 and 33a extending from the diaphragm 29 are intended to be such that when the diaphragm is in its central or at rest position neither one of the flags can be seen. When a greater pressure is exerted on the right-hand side of diaphragm 29, the diaphragm will be extended toward the left and the flag or indicator 33 may then be seen through the transparent window 45. In like manner, when the

diaphragm is extended to the right, the red flag or indicator 33a may then be seen through the transparent window 46. The drill hole 29 and the conduit 18 are intended to communicate fluid pressure from the nozzle member 15 into the space on the left-hand side of the diaphragm 29. When a greater pressure is communicated through this assembly of conduits the diaphragm is extended to the right and the indicator flag 33a will be visible through the transparent window 46.

The nozzle member 15 is provided with an opening 21 in its sidewall, and web member 44 has a small diameter conduit 19 therethrough extending from the circular space bounded by the wall of the nozzle member 15, the adjacent resilient washer 17a, and the body member 11. This small diameter conduit 19 extends from the circular space just mentioned to a point within the unremovable section 41 of the auxiliary housing 31. The specific positioning of the components of this small diameter conduit 19 may best be seen in Figure 1. This conduit 19 terminates at point 47 as illustrated. When the diaphragm 29 is positioned adjacent the surface of the auxiliary housing member 41 and the auxiliary housing member 42 placed against the diaphragm, the opening 47 which is the end of conduit 19 opens directly into one end of the conduit 28. In this manner, fluid pressure is communicated through conduits 19 and 28 into the space between the diaphragm 29 and the removable section 42. Thus, when greater fluid pressure is communicated from the right-hand side of the body member 11 than from the left-hand side and through the nozzle fitting 16, conduit 19, and through conduit 28 to the point on the right-hand side of the diaphragm 29, the indicator flag 33 is then moved to the left and may be seen through the transparent window 45. The utility of the indicator assembly may be best visualized upon reference to Figure 4. Thus, when greater pressure comes from cylinder 52, the indicator 33 extends into the transparent window 45 indicating that the left-hand cylinder is empty. In like manner, when the greater pressure is coming from cylinder 51, this pressure is communicated through the nozzle member 15, opening 20, and through conduit 18 to the left-hand side of the diaphragm 29, thereby causing the red flag or indicator 33a to become visible through the transparent window 46 and the flag in the window 46 indicates that the cylinder 52 is empty.

Referring to Figure 4, the installation of the changeover and indicator assembly of my invention may be seen. LPG storage tanks 51 and 52 are connected respectively by conduits 53 and 54 to the respective nozzle members 15 and 16. Connected to the threaded L 31a is a conduit 57 containing a check valve 58. This conduit 57 is attached to a pressure reducing regulator 59 which in turn is connected to the gas main or conduit 60 which is intended to conduct the gas to its ultimate use.

In the operation of my apparatus, when high pressure gas from cylinder 51 is conducted through conduit 53 and through the nozzle member 15, the gas passes through the valve seat 34 and around the edges of the magnet element 22, conduit 27a and out the outlet conduit 38. When the high pressure gas originates from the cylinder 52 it flows through the conduit 54 to the nozzle member 16 and thence through the valve 35 and around the side of the magnet 23,

through conduit 27b, and thence out the side conduit 38. When both cylinders 51 and 52 contain liquid, the pressure of the vapor over the liquid is about the same. And this equal pressure from the cylinders is communicated through the conduits 53 and 54 into the corresponding nozzles 15 and 16. Accordingly, the pressure throughout the main conduit is approximately the same and is about that of the pressure over the liquid in the cylinder. When the pressure is equalized throughout the conduits 27a and 27b and the handle 14 is positioned as indicated in Figures 1 and 3, the north pole of the magnet 24a repels the north pole of the magnet 22 and forces the resilient sealing member 25 against the valve seat 34 and closes the cylinder 51 against the flow of gas. Under these same conditions, the south pole of the magnet 24b attracts the adjacent north pole of the magnet 23 and removes the resilient member 26 from contact with the valve seat 35 and, accordingly, gas can flow from cylinder 52 through the nozzle 16 and out the side delivery tube 38 to the appliances for use. The arrow 49 points to the outer end of the handle 14 and accordingly indicates that the cylinder to the right is the one from which gas is being withdrawn. Under these conditions, pressure from the cylinder 52 is communicated through the conduit 54, opening 21, and conduit 19 to the right-hand side of the diaphragm 29. Thus, pressure on the right-hand side of this diaphragm tends to move the diaphragm from right to left. This diaphragm will move in this direction only if there is a sufficient pressure differential. This pressure differential will exist only under the conditions when the tank 51 is empty or has been removed from the line for replacement. However, when the tank 51 is full or contains at least some liquefied gas, the pressure from this liquid is communicated through the conduit 53 into nozzle 15 and thence through the opening 20, conduit 18 and to the left-hand side of the diaphragm 29. This pressure then tends to move the diaphragm from the left to the right. Thus pressures from both cylinders 51 and 52 are equal, and, of course, there is no movement of the diaphragm 29 and neither of the flags 33 or 33a can be seen. However, when pressure in the storage tank 52 diminishes sufficiently, the flag 33a becomes visible through the right-hand window 46 and the red flag visible through this window indicates that the pressure on the cylinder 52 has been decreased. And under this pressure decrease the tank 52 is indicated as empty or substantially empty and needs replacement.

When the contents of tank 52 have been withdrawn until no liquid remains in the tank, a substantial drop in pressure results and the greater pressure in tank 51 overcomes the magnetic force acting on valve member 25, moving the latter away from seat 34. The flow of gas through seat 34 results in a pressure drop of sufficient magnitude to overcome the magnetic force urging valve 25 closed, so long as gas is withdrawn via line 60. The appearance of the flag 33a in window 46, indicating depletion of the contents of tank 52, signals the operator or householder that this tank needs to be removed and replaced. He should first turn handle 14 so that arrow 49 points toward tank 51, to indicate that that tank is now on "supply." This reverses the position of the magnets, causing valve 25 to be held open by magnet 24b and valve 26 to be closed by magnet 24a. However, should the oper-

ator remove tank 52 before reversing handle 14 no harm will be done because the pressure drop across valve seat 35 is more than enough to overcome the magnetic attraction between magnets 23 and 24b, and hence valve 26 will immediately close, thus acting in the manner of a slug check valve.

When the tank has been replaced by a full tank, and this full tank opened to the indicator and changeover assembly, high pressure will be communicated through the conduit 54, through opening 21, through conduits 19 and 28 to the right-hand side of the diaphragm 29. High pressure on this side of the diaphragm will move the diaphragm at least to the central position and the indicator flag will disappear from the window 46. Under these conditions, the pressures on both sides of the diaphragm 29 are about the same and the indicator flag will not be visible through either of the windows 45 or 46.

In a similar manner, when the tank 51 has become depleted of its liquid content, no more gas can then flow through the valve 34 and high pressure gas will then come from tank 52 through the valve 35 and will open this valve sufficiently against the effect of the magnet 23 to permit full use of the gas from the tank 52. This high pressure gas in the conduit 27b and 27a will force the magnet 22 to close the valve 34 against the attractive force of unlike poles of the magnets 24b and 22. The low pressure from the empty tank 51 will then be communicated through the opening 20, through the conduit 18 into the space on the left-hand side of the diaphragm 29 and the diaphragm will be displaced toward the left, which movement places the indicator flag 33 in the window 45. Since the indicator flag may be seen through the window 45, the indication is that the tank 51 is empty and needs replacing. When tank 51 has been replaced by a full tank, high pressure is then communicated through this assembly of conduits into the space on the left-hand side of the diaphragm 29 and this diaphragm will be again moved to its neutral position and the flag will disappear from the window 45 indicating that both tanks 51 and 52 contain liquefied petroleum gas at high pressures.

The construction of my changeover and indicator assembly is relatively simple since three die casting parts are all that are necessary for the construction of a complete unit. The main body member 11 is one of the cast elements, the removable section 42 of the indicator housing is a second element, and the handle and rotor assembly, 14 and 13, is the third of the cast elements. The nozzle fittings 15 and 16 are standard elements and may be constructed in any manner desired. The magnets 24a and 24b may, if desired, be a single magnet. In this case, an opening should be provided in the center thereof for installation of the rotor assembly on the spindle 12. However, operation is equally efficient when magnets 24a and 24b are separate or individual magnets. The magnets 22 and 23 are sufficiently smaller in diameter than the conduits in which these magnets are disposed so that the gaseous material will be relatively unobstructed in its flow around these magnets. The resilient washers 17 and 17a are of such material and construction and are so positioned in the body member 11 that gas can easily flow around these elements in either direction. Small diameter sections 27 and 27a and the small diameter conduits 18, 19 and 28 may be drilled. The production of small diameter conduits through

castings by drilling is standard practice in construction of elements of this nature. By maintaining the overall length of the main body member 11 as short as possible will facilitate the drilling of these small diameter conduits. Unwanted conduits made when drilling wanted conduits may be threaded and sealed with threaded plugs. Such construction is standard practice and is well known by those skilled in the art.

The changeover and indicator assembly, herein described, is given merely as an example and the apparatus of my invention should not be limited thereby but only by the following claims.

I claim:

1. In a liquefied gas system, an automatic changeover valve mechanism comprising, in combination, a body member provided with an inlet port for each of two supply sources, a common outlet port, a conduit connecting each of said inlet ports with said common outlet port, each of said inlet ports terminating as a valve seat, a free floating valve sealing member adjacent each valve seat, each valve sealing member being so positioned as to close an inlet port when the force applied to the sealing member in the direction of closure is greater than the force applied in the opposite direction, and a magnet for supplying an increment of force to said valve sealing member to urge said sealing member against its seat in a closed position.

2. In a liquefied gas system, an automatic changeover valve mechanism comprising, in combination, a body member provided with an inlet port for each of two sources of supply, a common outlet port, a conduit connecting each of said inlet ports with said common outlet port, each of said inlet ports terminating within said mechanism as a valve seat, a free floating valve sealing member adjacent each valve seat, said each free floating valve sealing member comprising a resilient sealing element and a permanent magnet, said each free floating valve sealing member being so positioned as to close an inlet port when the force applied to the sealing member in the direction of closure is greater than the force applied in the opposite direction, and a magnetic means to supply at least a portion of the closing force.

3. In a liquefied gas system, an automatic changeover valve mechanism comprising, in combination, a body member provided with an inlet port for each of two sources of supply, a common outlet port, a conduit connecting each inlet port with said common outlet port, each of said inlet ports terminating within said mechanism as a valve seat, a free floating valve sealing member adjacent each valve seat, said each free floating valve sealing member comprising a resilient sealing element and a permanent magnet, said each free floating valve sealing member being so positioned in one each of said conduits as to close an inlet port when the force applied to the sealing member in the direction of closure is greater than the force applied in the opposite direction, a magnetic means to supply at least a portion of the valve closing force, said magnetic means comprising a rotatable permanent magnet disposed outside of said body member.

4. In a liquefied gas system, an automatic changeover and indicating valve mechanism comprising, in combination, a body member provided with a first conduit extending longitudinally therethrough, a second conduit leading from the exterior of said body member to a midpoint

longitudinally of said first conduit, a third conduit in said body member extending from a point near one end of said first conduit to a point in an auxiliary housing disposed at one side of said body member and at a midpoint longitudinally of said body member, a fourth conduit in said body member extending from a point near the other end of said first conduit to a point in said auxiliary housing, a pressure responsive diaphragm in said auxiliary housing between the points of communication of said third and fourth conduits and said auxiliary housing, indicating means in communication with said diaphragm to indicate its position; a nozzle means threaded into each end of said first conduit in said body member thereby forming valve seats, an auxiliary opening in said nozzle members, a resilient ring member disposed between each of said nozzle means and said first conduit and forming fluid tight seals therebetween, said auxiliary openings, the spaces bounded by said resilient ring members, said nozzle means and the inner wall of said first conduit in said body member and said third and fourth conduits forming passages from said nozzle means to points in said auxiliary housing on either side of said diaphragm; a free floating valve sealing member adjacent each valve seat, said each free floating valve sealing member comprising a resilient sealing element and a permanent magnet, said each free floating valve sealing member being so positioned in said first conduit in said body member as to form a seal between said resilient sealing elements and said nozzle means when the force applied to said sealing members in the direction of closure is greater than the force applied in the opposite direction, like poles of said permanent magnets being disposed adjacent said resilient sealing elements, a magnetic means to supply at least a portion of the valve closing force, said magnetic means comprising a rotatable permanent magnet disposed between the aforementioned permanent magnets.

5. In the system of claim 4 wherein said rotatable permanent magnet is disposed outside of said body member and one end of which is adapted to attract an adjacent end of one of the first mentioned magnets, and to repel the adjacent end of the other of the first mentioned magnets.

6. In the system of claim 5, indicating means to indicate the pair of magnet ends mutually attracting each other.

7. In a system for dispensing liquefied gas consisting of two containers for the liquefied gas, a delivery line from each container, a check valve in an outlet line, said outlet line being in fluid communication with a pressure reducing valve and said pressure reducing valve on its outlet side being connected with a line for delivering gas to appliances, and an automatic indicating changeover valve assembly connected with said two gas delivery lines and with said outlet line communicating with said pressure reducing valve, said automatic changeover valve comprising, in combination, a body member provided with a first conduit extending longitudinally therethrough, a second conduit leading from the exterior of said body member to a midpoint longitudinally of said first conduit member, said second conduit connected with said outlet line containing said check valve, a third conduit in said body member extending from a point near one end of said first conduit to a point in an auxiliary housing disposed at one side of said

body member and at a midpoint longitudinally of said body member, a fourth conduit in said body member extending from a point near the other end of said first conduit to a point in said auxiliary housing, a pressure responsive diaphragm in said auxiliary housing between the points of communication of said third and fourth conduits and said auxiliary housing indicating means in communication with said diaphragm to indicate its position; a nozzle means threaded into each end of said first conduit in said body member thereby forming valve seats, one each of the other ends of said nozzle means being connected with one each of said gas delivery lines, an auxiliary opening in said nozzle members, a resilient ring member disposed between each of said nozzle means and said first conduit and forming fluid tight seals therebetween, said auxiliary openings, the spaces bounded by said resilient ring members, said nozzle means and the inner wall of said first conduit in said body member and said third and fourth conduits forming passages from said nozzle means to points in said auxiliary housing on either side of said diaphragm; a free floating 25 valve sealing member adjacent each valve seat, said each free floating valve sealing member

comprising a resilient sealing element and a permanent magnet, said each free floating valve sealing member being so positioned in said first conduit in said body member as to form a seal between said resilient sealing elements and said nozzle means when the force applied to said sealing members in the direction of closure is greater than the force applied in the opposite direction, like poles of said permanent magnets being disposed adjacent said resilient sealing elements, a magnetic means to supply at least a portion of the valve closing force, said magnetic means comprising a rotatable permanent magnet disposed between the aforementioned permanent magnets.
